UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END CONSTRUCTION.

1,209,087.

Specification of Letters Patent. Patented Dec. 19, 1916.

Application filed June 1, 1914. Serial No. 842,050.

To all whom it may concern:

Be it known that I, JACOB H. WEISBROD, a citizen of the United States, residing at St. Louis, Missouri, have invented a certain 5 new and useful Improvement in Railway-Car End Construction, of which the following is a full, clear, and exact description, such as will enable others skilled in the art to which it appertains to make and use the 10 same, reference being had to the accompanying drawings, forming part of this specification, in which—

Figure 1 is an elevational view of a car end of my improved construction. Fig. 2 15 is a vertical section taken approximately on the line 2—2 of Fig. 1. Fig. 3 is a horizontal section taken on the line 3—3 of Fig. 1. Fig. 4 is an elevational view of a portion of a modified form of my improved car end. 20 Fig. 5 is an elevational view of a portion of a further modified form of the car end. Fig. 6 is a horizontal section taken on the line 6—6 of Fig. 4. Fig. 7 is a horizontal section taken on the line 7—7 of Fig. 5. 25 My invention relates generally to railway cars and more particularly to a pressed metal structure which forms the end wall of a car.

In railway cars, and particularly those 30 designed for and used in the transportation of freight, the end portions of the car body and the end walls are subjected to strains and stresses resulting from service shocks and vibrations and also by reason of the 35 sudden starting and stopping of the cars, and the shifting of the load and contents of the cars while the latter are in transit.

One of the principal objects of my invention is to construct a car end from a plurality 40 of sections of material, preferably sheet metal, each section being reinforced and stiffened by one or more pressed ribs or corrugations, said sections having their meeting edges bent to form interlocking reinforcing ribs or corrugations, thus providing 45 a comparatively simple, inexpensive car end which can be readily combined with an ordinary car underframe and superstructure, and which end, by reason of its being 50 stiffened and reinforced, will be very effective in resisting such strains and stresses as may result from shifting loads, ordinary service shocks and vibrations, or collisions.

In order to comply with the Government 55 regulations relating to cars utilized for

transportation of explosives, it is necessary to provide car ends which are entirely devoid of projections, such as rivet or bolt heads, on their interior faces, for, if such construction were employed, it would be possible 60 for a box or package of explosives when shifted suddenly within the car to strike against the projecting head of a bolt or rivet, and thus develop sufficient impact to set off or effect a discharge of the explosives. 65 Likewise it would be possible for a bolt or rivet when subjected to a blow from the exterior of the car to perform the functions of a hammer and transmit to a box or package of explosives positioned against the inner 70 face of the car end, sufficient impact to effect a discharge of said explosives.

With this consideration in view, it is one of the objects of my invention to construct a car end having a substantially smooth flat 75 inner face, which car end is made up of a number of panels, portions of which latter are bent and shaped so that the heads on the inner ends of the rivets or fastening devices which unite said sections or panels are 80 inset a substantial distance with respect to the inner face of the completed end.

With the foregoing and other objects in view, my invention consists in certain novel features of construction and arrangement of 85 parts, hereinafter more fully described and claimed.

The car end illustrated in the accompanying drawings, and particularly Figs. 1 and 3 comprises three vertically disposed sections or panels which are approximately equal in width, but it will be understood that the number of panels may be increased if desired and likewise that said panels can be of different widths, as for instance, a comparatively wide intermediate panel and comparatively narrow side panels, or comparatively wide side panels and one or more comparatively narrow intermediate panels. 90 95

The side panels 10, which are preferably formed of sheet metal and of sufficient length to extend from the underframe to the roof structure, are duplicates, which provision is desirable from a manufacturing standpoint for the reason that they can be 100 readily formed with a single die and may be used interchangeably. Formed in each side section and preferably at a point midway between its side edges is a vertically 105 disposed outwardly extending reinforcing 110

rib or corrugation 11, the same being substantially U-shape in horizontal section. The ends 11^a of these ribs or corrugations gradually decrease in depth until they merge 5 into the main body of the sheet.

The outer edge 12 of each side section or panel is preferably bent rearwardly in order to be readily combined with the corner post of the car body. The inner edges of each 10 panel or section 10 is bent outwardly to form a reinforcing rib 13 which is substantially L-shape in horizontal section and the edge of the outer leg of this rib or corrugation is bent inwardly as designated by 14 to 15 form a retaining lip or flange which is adapted to engage behind a corresponding rib or corrugation which is formed on the side of the intermediate section or panel. The intermediate panel or section 15 is 20 formed from a single piece of sheet metal and provided at its center with an outwardly projecting vertically disposed rib or corrugation 16 which is substantially a counterpart of the rib or corrugation 11 of the side 25 panel.

The side edges of the intermediate panel are bent outward to form reinforcing ribs 17 which are substantially L-shape in horizontal section. When all of the panels forming 30 the end are properly assembled these ribs 17 occupy positions within the ribs 13 of the side panels and the retaining lips 14 engage behind the outwardly projecting portions of the ribs on the center panel, thereby 35 practically interlocking the overlapping ribs.

Fastening means, preferably in the form of rivets 18, pass through the overlapping portions of the ribs 13 and 17, and as said 40 ribs project outwardly from the body portions of the panels or sections of which the car end is formed, the heads on the inner ends of these rivets are inset a substantial distance with respect to the inner face of the car end. By virtue of such construction it 45 will be impossible for the rivets or attaching devices to transmit the impact of blows received by the heads on the outer ends of said rivets, to freight, such as boxes or packages of explosives which may be positioned 50 immediately against the inner face of the car end.

The car end is materially reinforced and strengthened by the interlocked ribs 13 and 17, and such reinforcement is augmented by 55 the provision of ribs or corrugations 11 and 15 in the centers of the individual panels.

In order to further reinforce and stiffen 60 the end, the sheets forming the panels or sections may be provided with vertical rows of short horizontally disposed ribs or corrugations 19 as illustrated in Fig. 4, said short ribs or corrugations being pressed outward from the panels between the vertically disposed ribs or corrugations.

65 A further means of reinforcing and stiff-

ening the car end is through the use of buckle plates, one of which is illustrated in Figs. 5 and 7. These plates are buckled or provided with one or more comparatively wide ribs or corrugations which are pressed 70 outwardly, and which extend vertically of the plates and approximately equal the length of the ribs or corrugations formed on the edges of said plates.

A car end of my improved construction is 75 comparatively simple, can be easily and cheaply manufactured and by providing the individual sections with ribs or corrugations, certain of which overlap and interlock at the edges of said sections, the end is reinforced and stiffened to a maximum degree, and it will be effective in resisting all internally or externally applied shocks or blows and all service strains and vibrations.

As hereinbefore described, the heads on 80 the inner ends of the rivets or bolts utilized in connecting the overlapping edges of the sections or sheets forming the car end, are inset with respect to the inner face of said end, and thus cars equipped with my improved end are applicable for use in the transportation of explosives, inasmuch as the 85 ends in construction, comply with the regulations and requirements of the Government relating to transportation of explosives. 90

It will be readily understood that minor 95 changes in the size, form and construction of the various parts of my improved car end can be made and substituted for those herein shown and described, without departing from the spirit of my invention, the 100 scope of which is set forth in the appended claims.

I claim:

1. A car end comprising a plurality of 105 vertically disposed sheet metal sections or panels, the meeting edges of which are bent outwardly to form overlapping ribs or corrugations, attaching means seated in the overlapping ribs or corrugations to connect 110 them to form post like reinforcements and with the inner ends of said attaching means outside the plane of the inner face of the end, and outwardly pressed corrugations forming transverse reinforcements between 115 the post like reinforcements so formed.

2. A car end comprising a series of plates, each provided with an outwardly pressed vertically disposed reinforcing rib or corrugation and the meeting edges of which plates 120 are provided with outwardly pressed reinforcing ribs or corrugations which are adapted to overlap and interlock, said plates being provided with stiffening corrugations extending intermediate said reinforcing ribs. 125

3. A car end comprising a series of plates, each provided with an outwardly pressed strengthening rib or corrugation terminating short of the edges of the plates, the meeting edges of which plates are provided 130

with outwardly pressed reinforcing ribs or corrugations terminating short of the edges of the plates which are adapted to overlap and interlock, and attaching means seated in the overlapping portions of said last mentioned ribs or corrugations.

4. A car end comprising a series of plates conjoined on vertical edges, the central portions of which plates are corrugated, and the meeting edges of which plates are provided with conjoined outwardly pressed ribs or corrugations which terminate short of the edges of the plates.

5. A car end comprising a series of plates,

the central portions of which are deformed, 15 the meeting edges of which plates extend vertically and are provided with outwardly pressed L-shaped ribs or corrugations which are adapted to overlap and interlock, and fastening means seated in the overlapping 20 portions of said ribs or corrugations.

In testimony whereof I hereunto affix my signature in the presence of two witnesses, this 22nd day of May, 1914.

JACOB H. WEISBROD.
